AMOS ADOLPHUS GLISSON, OF FORT WORTH, TEXAS.

ADVERTISING DEVICE.

1,262,191.

Specification of Letters Patent. Patented Apr. 9, 1918.

Application filed November 25, 1916. Serial No. 133,432.

To all whom it may concern:

Be it known that I, AMOS A. GLISSON, a citizen of the United States, residing at Fort Worth, in the county of Tarrant and State of Texas, have invented a new and useful Advertising Device, of which the following is a specification.

This invention has reference to advertising devices and its object is to provide an advertising device of such character that it may be manufactured so cheaply as to warrant the free distribution of the devices among customers or prospective customers, or where the advertising nature of the device will be effective, and at the same time provide so useful a device that there is an incentive to preserve the structure and frequently use it, thus enhancing its advertising value.

The invention is intended particularly for use upon a desk, and to contribute to the preservation of the device it is so constructed as to serve as a ruler, with the special advantage over ordinary rulers that through its use the necessity of "spotting" or otherwise marking papers or other materials preparatory to the drawing thereon of true or exactly parallel lines, with desirable spacings, may be avoided.

Because of the construction of the device whereby it may be used after the manner of a parallel ruler, that is, for drawing parallel lines, the device includes a frame having a longitudinal bar at what constitutes the upper portion of the device when in use. This bar is so constructed and arranged that pictorial representations may be produced upon it in a manner causing the representations to assume a perspective effect, especially when the device is lifted from the desk or is lying upon a surface of a color differing from that of the device itself. When the device is lifted free from the desk or other surface the pictures or other like advertising matter is viewed against the background distant from the pictorial representations, with the result that such pictures appear to be suspended in air and to stand out away from their distinctly seen base or background, with the result that extraordinary perspective effects of attention-compelling natures are produced and maintained.

The invention will be best understood from a consideration of the following detailed description, taken in connection with

the accompanying drawings forming part of this specification, with the further understanding that while the drawings show a practical form of the invention, the latter is not confined to any strict conformity with the showing of the drawings, but may be changed and modified so long as such changes and modifications come within the scope of the appended claim.

In the drawings:

Figure 1 is a plan view of the advertising device applied to a sheet of blotting paper and positioned for use upon a sheet of paper or other material of a different character.

Fig. 2 is a cross-section of the advertising device applied to a sheet of blotting paper.

The device comprises a frame 1 which may be and usually is of rectangular form much longer than wide, and comprises a wide side bar 2 and a narrow side bar 3, together with end bars 4 and 5, respectively. On the edge of each end bar toward the interior of the frame are pointers 6, 7, and 8, although the device is not limited to three pointers, and these pointers are located correspondingly definite distances from the inner edge of the bar 2, such edge being indicated at 9. Considering the pointers 6, 7 and 8 as being equi-distant from each other with the pointer 6 separated from the edge 9 by a like distance and the pointer 8 separated from the inner edge of the bar 3 also by a like distance, it may be assumed that the spacing is by quarter inches; that is, the pointer 6 is a quarter of an inch from the edge 9, the pointer 7 is a half inch therefrom, and the pointer 8 is three-quarters of an inch therefrom, with the inner edge of the bar 3 spaced one inch from the edge 9.

If the measurements stated be those adopted, then the bar 3 may be one-quarter of an inch wide at its approximate ends in which case its outer edge will be spaced one and one-quarter inches from the edge 9. To utilize the bar 3 in spacing, the extremities of the bar are formed into pointers 10, but these pointers are directed away from each other, while the pointers 6, 7 and 8 are directed toward each other and confined within the space defined by the interior of the frame. The pointers 10 are formed by notching the corners of the frame remote from the bar 2, the notches being indicated at 11. Each end bar 4 and 5 may have fractional or other measurement indications 12 printed thereon and the edge portion 9 of

the bar 2 has division marks 13 and numbers 14 representing some chosen unit of measurement, such as inches. The divided edge 9 of the bar 2 constitutes a ruler and the 5 measuring indications may be sub-divided as much as desired.

The bar 2 is made of considerable width and provides a corresponding considerable 10 space for advertising matter, which is indicated in the drawings by the one word "Advertisement" and by pictorial representations 15 15.

The bar 3 is provided with expanded portions 16 so shaped as to conform to and contain pictorial representations 17, which in the particular showing of the drawings are perspective representations. Since the advertising device has been described as particularly useful on desks in offices, the pictorial representations chosen in the particular 20 showing of the drawing, represent office furniture of various kinds, and parts thereof.

Where the advertising device is used in 25 other connections the pictorial representations correspond, and, of course, the assumption is that the advertising matter of a printed nature corresponds to the showing of the pictures.

It is quite feasible to display advertising 30 matter on both sides of the device, but this is so apparent that no attempt is made to show the obverse side of the device. The fact that advertising matter may be displayed on both sides of the device is indicated by the word "Over" in certain of the 35 corners of the device.

In order to attach a blotter, indicated at 18, the end portions of the bar 2 have 40 punched out tongues 19 so arranged as to engage that face of the blotter remote from the bar 2 and clamp the device to the blotter in a manner to hold it against accidental separation from the blotter in the ordinary 45 course of handling. It will be understood that the tongues 19 may be replaced by any form of grip, clip or fastening desired.

The spacing between the numerals 14 may 50 also be utilized for advertisement, as indicated by the line 20 of words immediately adjacent to the edge 9.

When the device is carried by a blotter or the blotter is carried by the device the blotter definitely and uniformly spaces the bar 55 2 from any surface upon which the blotter lies. The consequence is that the edge 9, which may be beveled if desired, is spaced away from the surface and blurs are avoided in cases where the surface is to be ruled 60 with ink or the like.

In the drawing the surface to be ruled is considered as a surface of a sheet 21 of paper. Assuming that a line 22 has been ruled upon the paper sheet 21 and it is desired to 65 produce other lines upon the sheet in par-

allel relation to the line 22, any pair of pointers 6, 7 or 8, or the inner edge of the bar 3, or the pointers 10 are brought into coincidence with the line 22, thus spacing the edge 9 the required distance from the 70 line 22, so that the next line drawn along the edge 9 as a guide will be so spaced from the line 22. For instance, with the arrangement shown in the drawings a succession of lines separated by a quarter of an inch may 75 be produced upon the sheet 21 with ease and certainty. The same is true if the spacing desired be a half inch or three-quarters of an inch or an inch, or an inch and a quarter.

Owing to the constant presence, the frequent usefulness and the impressive novelty of the form of the device, the eye and the mind of the person possessing it or of those who may be in its presence, are primarily, strongly and frequently constrained to observe and consider the perspective matter or illustrations. There follows, therefore, the psychological result that the observer is brought into an emphasized appreciation of the advertisement as a whole, or of the thing 90 or things advertised, which cannot be produced through the use of previously devised mediums.

Because the device is of a time-saving 95 nature which premiumizes its retention for long and frequent usage, and under such usage it would easily be subject to damage if composed of very soft or fragile material; and inasmuch as the usual expedient of embossing or otherwise specially treating the 100 illustrations of other portions of the advertisement may be done with some advantages through the use of tough or comparatively strong materials, the device may preferably be made of a comparatively substantial and 105 permanent character by constructing it of metal or celluloid or the like.

Inasmuch as the prime or main purpose of advertisement is to secure frequent and concentrated favorable attention to or for 110 the object exploited or presented for public consideration, and the advertising value of the medium employed for the purpose is measured or approximated by the attention-compelling force with which its elements 115 are displayed and the persistency with which its advertising message is presented, and as the new and improved elements of direct and frequent usefulness and the novelty of form provided in the present structure are 120 strongly conducive to an appreciation leading to its preservation and to an ever-increasing impressiveness of the advertisement associated with or forming a part of it, in consequence of its being under more 125 or less constant observation, its advanced and meritorious status in the field or art to which it appertains becomes at once manifest and demonstrable.

In order to readily direct the eye of the 130

user from the numbers 12 to the indicating ends of the pointers 7, 8 and 10, these pointers may contain representations 23 of arrows or the like.

5. What is claimed is:—

An advertising device comprising an elongated rectangular frame of substantially flat material having long side bars and relatively short end bars connecting the side bars, one of the side bars being relatively narrow and provided with enlargements projecting beyond both long edges of the narrow side bar with each enlargement associated with the corresponding enlargement of the other edge of said narrow side bar, and another side bar relatively wide and free from projections on its long edges, the matching projections of the narrow side

bar having pictorial representations thereon in perspective, with the outlines of the projecting parts conforming to the outlines of the perspective representations, whereby the relation of said pictorial representations to the open space within the frame and the open space outside of the frame beyond the narrow side bar displays the perspective effect of the pictorial representations, said wide side bar being capable of use for other than advertising purposes.

In testimony that I claim the foregoing as my own, I have hereto affixed my signature in the presence of two witnesses.

AMOS ADOLPHUS GLISSON.
